UNITED STATES PATENT OFFICE

2,409,770

APPARATUS FOR CONTINUOUSLY PROCESS-
ING METAL STRIPS

Frank W. Lorig, Lakewood, Louis L. Miller, Garfield Heights, and Frank E. Robinson, Shaker Heights, Ohio, assignors to The American Steel and Wire Company of New Jersey, a corporation of New Jersey

Application April 15, 1941, Serial No. 388,708

4 Claims. (Cl. 271—2.3)

1

This invention relates to the continuous processing of metal strips and, more particularly, is directed to an improved means for performing a heat treatment on one or several strips of steel wherein the exposure of the strip to the processing treatment can be very carefully regulated and critically controlled.

There are some types of steel which are produced in strip form, such as silicon steels intended for use in electrical apparatus, which strips, in order to develop the optimum in physical or electrical properties, have to be subjected to carefully controlled heat treatment. In the case of electrical sheets, such processing is carried out by batch annealing or normalizing processes which are facilitated by the physical shape of the material being treated, rendering special equipment in giving effect thereto unnecessary. In the case of strip steel, however, the commercial requirements are such as to render the production of all widths of strip steel, ranging from 6" wide, or less, up to 42" and wider, necessary. The elaborate heating furnaces and appurtenant equipment that must be applied in performing the continuous annealing of such strips, renders prohibitive the provision of separate processing lines for each strip, or each width of strip to be operated upon. It is, therefore, one of the main considerations of the present invention to provide a unitary line for the continuous heat treatment of one or more strips irrespective of the widths thereof up to a predetermined maximum.

In accordance with the present invention, it is contemplated that, either one strip of maximum width, or a plurality of strips of less widths, the total of which does not materially exceed the strip of maximum width, can be processed simultaneously, with each strip being independently controlled and regulated in its course through the processing zones of the line without interference with or from the adjacent strips being processed.

In the drawings:

Figure 1 is a partial plan view of the improved apparatus of this invention;

Figure 1^a is a continuation of the apparatus, this view continuing from the line *a—a*, Figures 1 and 1^a; Figure 1^b is a further continuation of the apparatus, this view continuing from the line *b—b*, Figures 1^a and 1^b; Figure 1^c is a further continuation of the apparatus, the view continuing from the line *c—c*, Figures 1^b and 1^c;

Figure 2 is a partial sectional elevation of the apparatus, the view being taken along the center line of Figure 1;

Figure 2^a is a continuation of Figure 2, the 55 A, from which one or more strips are paid suc-

2

showing of this view continuing from the line *a—a* of Figures 2 and 2^a; Figure 2^b is a still further extension of the apparatus, the view continuing from the line *b—b* of Figures 2^a and 2^b; Figure 2^c is a still further extension of the apparatus, this view continuing from the line *c—c* of Figures 2 and 2^c;

Figures 3, 4, and 5 are side elevational, rear elevational, and plan views, respectively, of a typical form of aligner;

Figures 6 and 7 are side elevational and rear elevational views, respectively, of one of the strip forwarding mechanisms;

Figures 8, 9, and 10 are side elevational, plan, and end views, respectively, of one arrangement of pinch rolls adapted to control the advancement of the strip;

Figures 11 and 12 are side elevational and transverse elevational views, respectively, of one arrangement of master pinch rolls;

Figures 13 and 14 are a fragmentary detailed view (shown partly in section) and a rear elevational view, respectively, of one of the apparatus units designated by the letter V in the line illustrated in Figures 1^c and 2^c;

Figures 15 and 15^a are schematic planar projections showing how one form of apparatus embodying the present invention can accommodate different widths and numbers of strips, and the relative placement thereof as to the catenary pinch rolls (designated by reference numerals prefixed with the letter "M") and wind-up reels (designated by reference numerals prefixed with the letter "X");

Figures 16 to 21, inclusive, each shows, in schematic planar projection, the placement of rolls in the catenary pinch roll unit and how different widths of strip, as illustrated in Figures 15 and 15^a may be accommodated therein in varying numbers.

Fig. 22 is a fragmentary side elevation of the catenary furnace employed in conjunction with the present invention;

Fig. 23 is a sectional elevation of the furnace, 45 taken on line XXII—XXII of Fig. 22;

Figs. 24 and 24A taken together illustrate a wiring diagram of the complete electrical control system of the apparatus, Fig. 24A being a continuation of the diagram of Fig. 24.

Referring now more particularly to the drawings, there is shown in Figure 1 a side elevational view of one form of equipment that gives effect to a preferred arrangement of the invention.

In general, a strip supply depot is indicated at

cessively through an aligner B, a connecting unit C, intermittently actuated pinch rolls D, from which the strip is guided past an accumulator pit F by aligner units E and G. From thence, the strip is passed through cleaning, rinsing, and drying units H, J, and K, through aligners L to a series of pinch rolls M¹ through M⁷, which are adapted to accommodate one or more strips of varying widths, and which are regulative individually to determine the rate of movement of each of the strips through the system, as will be described in detail hereinafter. From the pinch roll unit M the strip is conducted through aligners N and O, through a heating zone P, which is here illustrated in a form of catenary furnace. From the catenary furnace the strip is passed through a cooling zone Q, thence through other aligners and guide means R and S, to a master pinch roll unit T, from whence it is directed over an accumulator pit U, and thence to the take-ups X¹ through X⁷ through guide and control means V and W, all of which will be described more fully hereinafter.

As an example of the capacity and flexibility of one apparatus built in accordance with the present invention, similar to that shown in the accompanying drawings, such a line has been designed to handle from one strip 30" wide to seven strips 6" wide, or narrower. It will, of course, be understood that there is nothing critical about these dimensions, these being but illustratory of one arrangement, and capable of being varied within wide limits for the accommodation of a greater or lesser number of strips of different widths than those here specified. In any case, the number of strips usually depends on the individual widths of each, as dictated by the requirements of the orders being filled, and as applied to and limited by the capacity of the particular design of line employed. In furtherance 40 of the example given, however, the total strip width will not exceed 42". Stated another way, the width of the area occupied by all of the strips, which includes the spacing between adjacent strips, will not exceed 60". Within those limits, 45 or within greater or lesser limits for equipment especially designed therefor, any combinations of widths of strips may be run.

Referring once again to the drawings, the supply depot A may comprise a plurality of horizontal floor stand type reels 1 for serving strips to the line, seven in number having been shown so as to be consistent with the example already given. These may be of any approved construction and may be varied to suit the taste of the operator.

From the reels 1, the strip is passed through aligning device B which, in construction, corresponds to aligners L, N, O, and R, so that one description should suffice for all. By reference to Figures 3-5, each aligner is comprised of side frame members 2 which are set upon suitable mountings or bases 3 adjacent the floor, each side member in relation to the other being spaced therefrom so as to straddle the line of passage 60 of the strip. A pair of rolls 4 are journaled for rotation in the side frames 2, and are preferably provided with ball bearings so as to offer the least possible resistance to the passage of the strip therethrough when they are pressed in engagement therewith in performance of their flattening function. These rolls are preferably idle. Mounted upon the strip approach side of these aligning rolls, and arranged so that one falls 65 above and one falls below the passage of the 70

strip, is a pair of transversely extending plates 5 and 5', which are secured to the uprights 2, closely adjacent the ball bearing rolls already described. As will be observed in the plan view of Figure 5, these plates are provided with a plurality of holes 6 which provide bearings for vertical pin members 7, which pins can be selectively arranged in the holes in any number required to effect lateral spacing and restraint of the strips.

The tail end of one strip is fastened to the lead end of a new coil in any suitable manner, as has been indicated by the articulator C, which may be a device for welding the strip together in any approved manner.

Immediately following the welder there are arranged the welder pinch rolls D, which are shown in greater detail in Figures 6 and 7. It will be seen that this unit comprises a pair of housings 10 having an upper roll 11 revolvably journaled therein on stationary bearings 12. The lower roll 13 is revolvably journaled in the housings 10 upon slideable bearings 14 which are adapted to be raised and lowered toward and away from the upper roll 11. The slide bearings 14 of the lower roll are actuated by a plurality of arms 15 which are fulcrumed to the housings 10 by pivotal bearings 16 so as to be moved to raise and lower the slide bearings 14 by a fluid cylinder and piston arrangement 17. A motor 18 provides power to each of the rolls 11 and 13 through a suitable reduction gear unit 19 and drive couplings 20.

The normal position of the lower roll is one of spaced relation to the upper roll so that, normally, strips being moved through the line will pass between these rolls without contact therewith, at which time the rolls are idle. When any one of the strips being run nears the end of its length, the lower roll is raised by the fluid cylinder 17 so as to squeeze the strips. Simultaneously, the motor 18 is energized to drive the rolls 11 and 13 at surface speeds greater than the normal rectilinear speed of travel of the strip, whereby an amount of slack strip is induced to fall in the accumulator pit F. The pinch rolls continue to drive in this fashion until the end of that strip, which is about to become exhausted, reaches the connecting unit C, whereupon the pinch rolls D are automatically stopped but remain closed to secure the several strips, and particularly the length being operated on by the articulator, from being pulled forward into the slack pit F by their own weight. After the connecting step has been completed, the pinch rolls D are allowed to assume their normal inactive open position in order to permit the resumption of the feeding of the strips from the supply depot A.

It will be observed that this arrangement renders unnecessary the stopping of the strip beyond the accumulator pit during the connecting operation since, while this is going on, the remainder of the line beyond the looping pit F continues to operate at the ordinary speed, using the slack strip accumulated in the pit F until the connecting operation has been completed. With respect to the accumulator pit F, it is desirable that this be provided with a wooden lining 30 to prevent marring the surface of the strip. Also, it is desirable that the strip be led into and withdrawn from the pit by guide devices E and G which comprise a plurality of rolls 31, so spaced to prevent any sharp bends or breaks in the strip and which may be provided with vertically arranged spacers 32 similar to those previously described in the case of the aligner B for preventing the lateral displacement of the strips.

The cleaning, rinsing, and drying units H, J, and K may be of any approved construction so long as a thorough degreasing and cleansing of the strip is accomplished. As shown, these consist of an alkali washer 35, a cold water rinse 36, a hot water rinse 37 and a hot air dryer unit 38, through all of which the strip passes successively in the order as given. While the degreasing and cleansing apparatus thus described is composed of four separate units, it is essentially one phase of the processing line, its sole object being to remove all trace of grease or oil left on the strip from the rolling processes. This is particularly important in the case of silicon electrical steels, where such oil or grease form deposits of carbon when heated in a furnace similar to the catenary furnace herein illustrated.

The strip is then introduced to the catenary pinch roll M through an aligning device L, similar to those previously described. The catenary pinch roll unit M (Figures 8, 9, and 10) comprises a plurality of individual roll stands for accommodating pairs of rolls of different widths and arranged in different horizontal planes. A preferred arrangement is to have four levels of bases 40, 41, 42, and 43, for the accommodation of roll stands 45, 46, 47, and 48, respectively. Mounted in the stand 45 and carried on the base 40 are pairs of rolls M² and M³ which are of different widths, and which are independently driven by motors 52 and 53, respectively. Similarly mounted and driven on the remaining bases 41, 42, and 43 are other pinch rolls, comprising, in the case of the base 42, one pair of large rolls M⁴ adapted to accommodate one strip of the maximum allowable width. In the example given, these may comprise rubber-covered rolls, the pair of M⁴ being 9" in diameter by 5' 8" long, both rolls of the pair being driven through a common double reduction worm gear 55 by a motor 56. There are three pairs of rolls M¹, M² and M³, each 7½" in diameter by 21½" long, and three pairs of rolls M⁵, M⁶ and M⁷, each 7½" in diameter by 35" long, rolls M¹ and M⁵, and M³ and M⁷ being driven by motors 56 through reduction gear units 55.

From this arrangement, it will be seen in the plan view of Figure 9 that each of the pairs of pinch rolls described lies within the area defined by the passage of the strip, be the latter one or several. Thus, it is possible to accommodate one strip of maximum width by the roll M⁴, in which case none of the other rolls will be used, or to pass a plurality of strips, as shown in the elevational view of Figures 1 and 8, by deflecting them vertically as at S¹, S², S³, and S⁴, so that each is engaged by an independently powered set of rolls, respectively, of the proper width to accommodate the size of strip being acted upon in each case.

The accommodation of different numbers of strips of various widths will, perhaps, be better understood by reference to Figures 15 to 21, inclusive. Here are set forth, in planar projection, the different widths of strip that can be accommodated, showing the relation of strip width to the number of strips run, and how these are accommodated in the catenary pinch roll unit M in relation to the take-up blocks X¹ through X⁷, the numbering of the latter corresponding to that shown on Figures 1^c and 2^c. In Figures 15 to 21, inclusive, the strip may be considered as moving from the bottom to the top of the page, thus corresponding to the right to left movement thereof in the views of Figures 1 and 2. With this relationship established, Figures 15 to 21, inclusive,

become self-explanatory when it is borne in mind that the catenary pinch rolls are prefixed by the letter "M," with the take-up reels served by each being designated (though not shown) by the numerals bearing the prefix "X," as shown in Figures 1^c and 2^c.

From the catenary pinch rolls M the strips are passed through aligners N and O, the latter of which may be provided with a pinch mechanism 10 for holding the strips while threading the latter through the catenary furnace P and cooling zone Q, preparatory to initiating the operation of the line. Ordinarily, however, the aligner O, as in the case of the aligners N, as well as all those previously described, will exert no drag upon the strips when the line is in motion, the pinch mechanism being used only to facilitate the threading-up operation, and being of any design suitable to this purpose.

After leaving the pinch rolls O, the strip is passed through the catenary furnace P, one form of which may be, as illustrated, in the order of 30' 3" long inside, having an active width of 5' and a height of 5' 6". The cooling chamber Q 15 may be approximately 260' long, provided at the strip entrance end with a brick lining, but throughout the major portion of its length with a water jacket lining, whereby to extract heat from the strip.

20 The strips are supported in the form of a catenary on rolls 60 and 61, which are spaced about 40' apart, allowing a normal sag of strip of about 4' 6".

Heat may be applied to the furnace in any suitable way, electrical resistance units of nickel 25 chromium having proved satisfactory.

The hearth rollers 62 of the cooling zone are 30 preferably driven through chain connections (not shown) by a motor 63. The arrangement is such as to provide for the flat run-out of the strip until substantially all of the heat, down to room temperature, has been extracted therefrom. As has already been indicated, this latter operation has been facilitated by the circulation of water 35 through a water jacket that surrounds the major part of the enclosed run-out cooling zone Q.

Suitable aligners and guides R and S may be provided to allow for the extension of the cooling zone if this is found to be required.

50 The strip is then paid into the master pinch rolls T, which are shown in Figures 11 and 12, and comprise a pair of roll housings 65 spaced apart to stand, respectively, at each side of the passageway of the strip. A pair of rollers 66 are 55 journaled in anti-friction bearings 67 carried in these housings. The rolls are driven through a reduction gear unit 68 by a motor 69. The roller bearings 67 are carried in chocks 70 slidably mounted in the vertical windows in the housing 60 65 and are urged toward each other to cause the rolls firmly to grip the strip by means of a lever 71 fulcrumed to each of the housings as at 72, which is pressed against the upper roll chock 70 by a compression spring 73 acting through a link 65 rod 74. The compression of the springs 73 can be varied by adjustment of the screws 75 circumjacent to each of the link rods 74 and adjustable relative to a stationary screw bearing 76 on each of the housings 65, respectively.

70 The drive of the master pinch rolls T is connected electrically, as by a Ward-Leonard control system, with the catenary pinch rolls M and, insofar as practicable, synchronized with them. Inasmuch as it is inevitable that asynchronous tendencies will develop when a plurality of strips are

being run, there is provided interiorly of the furnace two transversely extending horizontal contact rods, as shown in Figures 23 and 24, one of which is arranged above the pathway of the travel of the strip, and the other of which is arranged below the pathway of the travel of the strip. These rods are aligned vertically in a plane which intersects the catenary of the strip substantially at the lowermost point of the sag, and are electrically energized. If the strip touches the upper contact rod, a signal is actuated exteriorly of the furnace indicating to the operator that the catenary of one or more strips has become too short, or, if the lower contact rod is touched by the strip, a different signal is actuated to indicate that the catenary of one or more of the strips has become too long. Which strip will have thus got out of phase, is determined by sighting through a peep-sight suitably arranged in the end of the furnace to allow for the inspection of the strip. Then, the appropriate catenary pinch rolls M are actuated either to speed up or slow down the advancement of the strip affected until the correct catenary condition has been restored. If desired, the speed of the motor for any one of the pinch rolls of the group M can be automatically and electrically controlled and varied by providing in the furnace in the place of or in addition to common contact rods, individual contact rods for each strip insulated from each other so that upon contact with the catenary of a particular strip the speed of the motor for the pinch roll controlling the catenary of that particular strip can be automatically varied as desired to restore the catenary to its normal position in the furnace.

It will be understood from the foregoing that the master pinch rolls T operate at a constant invariable speed to which the catenary pinch rolls M are correlated and ordinarily synchronized by the aid of an electrical system through which this may be done. In the event asynchronous tendencies develop as to some or all of the strips, a correction is made by speeding up or slowing down the affected pinch rolls of the group M, rendering it unnecessary to adjust the master pinch rolls T at the exit side of the furnace. For this reason, only one set of pinch rolls for the entire gang of strips is required at the unit T, thus simplifying the construction, and reducing the number of observations required of the operator, and the number of controls exercised by him, to one: to wit, that controlling the speed of revolution of the catenary pinch rolls M. In this fashion the strip is advanced uniformly at constant speed through the heating zone, and, in the case of several strips, each is given the same exposure to the heat and the same amount of time in the cooling zone, rendering conditions that are ideal for the processing of such materials as silicon electrical steels which require extreme care in the matter of heat treatment.

The master pinch rolls T deliver the strip past an accumulator pit U to guide rolls 81, arranged to define an arcuate pathway to minimize the bending of the strip when it is pulled out of the pit U. The strips are then passed through a plurality of drag and pinch units W to their respective reels X¹ through X⁷, which are separately powered to wind the strip up in coils. The units W impose sufficient drag to tension the strip as it is being wound on the reel in order that a tight coil may be formed. They also serve the purpose of holding the end of the strip, after it has been cut to discharge a coil from the reels,

thus to prevent its falling back into the pit U by its own weight.

Because the discharging of a coil of strip effects an interruption in the winding operation, the accumulator U is provided in order that the master pinch rolls T may continue to deliver the strip without causing an interruption in its movement throughout preceding portions of the line. Upon resumption of the coiling operation of any line 10 of strip thus interrupted, it is necessary for the winding reels to be speeded up in order to withdraw the resulting slack from the pit, thus to restore the normal operating condition. Usually 15 the strip leaves the master pinch rolls T and bridges the pit U in some elevated curve as at S⁵, in which position it is raised above the point wherein it contacts the lowermost guide rolls 81 on the unit V. The unit V, as is shown more in detail in Figures 13 and 14, is provided with a plurality of depending arms 75 which are equipped 20 at their lower end with strip-engaging rollers 76 and lateral guides 77 for engaging, respectively, the top surfaces and the edges of strip running thereby. The edge guides 77 may be lowered into 25 operative position, or removed from contact with the strip, as shown in broken lines of Figure 13. At their upper extremities, the arms 75 are pivoted for oscillation in planes vertically aligning with the strips, respectively. Each arm is provided with a small bell crank 78 which is adapted 30 to move the armature 79 of a solenoid 80 in response to variations in the catenary of the strip. The solenoid 80 is, in each case, arranged in a Thyatron circuit, whereby variations in the position of the armature of the solenoid cause the magnetic reluctance of its magnetic circuit to vary, thus causing variations in the excitation of the Thyatron circuit through which the take-up 35 motors 90 shown in Figure 1c, of the respective winding reels X¹ through X⁷ are controlled. It will be seen from Figures 1 and 13 that when an accumulation of strip is collected in the pit U as the result of a stripping operation of one or 40 more coils, the control arms 75 at the standard V are allowed to fall to the lowermost position of their cycle, as is indicated in solid lines in Figure 13. The armature 79 in this position is caused, through the bell crank 78, to be in the position wherein the magnetic reluctance of the solenoid 45 is at a minimum, thus effecting a corresponding response in the Thyatron circuit to cause the motor controlling the strip in question to speed up. The winding operation thus proceeds at an accelerated rate until the catenary of the affected 50 strip over the pit U has been caused to shorten to some position as at S⁵, which, it may be assumed, is its normal path. In this elevated position, the arm 75 overlying such strip is raised to the point shown in broken lines in Figure 13, whereby the armature of its associated solenoid 55 80 is withdrawn, causing a variation in the excitation of the solenoid and its associated Thyatron circuit, thus causing the winding reel motor to slow down to its normal speed for the remainder of the winding operation. In this manner a very sensitive and careful control is exercised over the winding of the processed strip. It will be understood that only so many of the 60 arms 75 as may be required to serve the number of strips being processed will be used in any given operation, the remainder being rendered inoperative by the shutting off of the unused winding reel motors and their associated control circuits.

In view of the foregoing reference now may be made to Figs. 24 and 24A.

It will be seen that the intermittently operated pinch rolls D which immediately follow the connecting unit C are driven by an electric motor 10 which is independently powered from a line separate from that which supplies power to the units following the initial pinch roll strand.

As is indicated in Figures 24 and 24A, the motors driving the catenary pinch rolls M¹ through M⁷, together with the motor driving the master pinch rolls T and the motors driving the take-up reels X¹ through X⁷ obtain their electrical power from one line and are successively connected across busses 200 and 201. The electrical power flowing through busses 200 and 201 is controlled by a Ward-Leonard control system which consists in this case of one motor generator set, whose voltage is controlled from zero on up to the maximum of the line input by means of a rheostat. It is apparent, therefore, that the speed of the motors driving the catenary pinch rolls, together with the motor driving the master pinch roll and the motors driving the take-up reels, can be varied simultaneously through this one control unit. The system is arranged in this manner in order to simplify the adjustment of speeds of the unit when changing from light to heavy gauges of strip running therethrough. When thin gauge material is passed through the unit the speed is increased due to the fact that for any given annealing temperature and furnace length the time required to anneal thin gauge strip is much shorter than that required for the heavier gauges.

It is to be understood, therefore, from the above, that the speed of the motor driving the master pinch rolls is constant for any given setting of the Ward-Leonard system; however, the speeds of the motors driving the catenary pinch rolls M¹ through M⁷ and the motors driving the take-up reels X¹ through X⁷ can also be varied by suitable control means other than that afforded by the Ward-Leonard control system.

As previously explained, the pinch rolls D following the connecting unit C are only intermittently driven and are never driven except when the lower roll is moved into contact with the strip by the hydraulic cylinder 17. From the explanation of the operation of unit D is as set forth above and it is quite clear that it is not necessary that the motor driving this unit be completely automatically controlled nor is it necessary that the motor be introduced into the Ward-Leonard control system.

As previously stated, it is impossible, due to roll slippage and non-uniformity of gage of the strip material, to maintain a fixed catenary in the loop in the strip for any extended period of operation. Therefore, because of these variables, the catenary at times will either lengthen or shorten, causing the strip to drag on the bottom of the furnace or to shorten to such an extent that undue tension will cause the strip to break because of its plasticity at the elevated annealing temperatures. In order to control the catenary loop of the strip, there is provided a signal system as previously described and illustrated in Figures 22 and 23. A sight opening is located at the end of the furnace and also in the side of the furnace at a point where the lowermost portion of the catenary exists. The signal system consists of a red and green lamp together with two different toned bells which are actuated when any given strip makes contact with the electrically energized contact bars. The green light is illuminated and one bell rings when the catenary loop is too long while the red light is illuminated and the second

bell rings when the catenary is too short. The two different toned bells are used to warn the operator in case he is not in a position to observe the signal lights. Both ends of the contact bars are supported by the refractory lining of the furnace and suitable leads attached to one end thereof are brought through the side walls of the furnace and are connected to the leads of one side of the current source while the other side of the current source is grounded to either the entering or exit rolls of the furnace. The electrical diagram for the signal system is shown at the left in Figure 24A.

After the operator has determined which strip has too long or too short a catenary loop, he then presses one of seven pairs of buttons which control the speeds of the seven motors which independently drive each of the seven pairs of catenary pinch rolls. The buttons are indicated by SD for "slow-down" and SU for "speed-up" for each of the seven motors. These control buttons are preferably located on a control board adjacent to the end of the furnace near the sight opening for observing the catenary loops of the strip lengths. If the operator pushes one of the buttons marked SU, he causes the current to flow through the full resistance of the field rheostat located in the field circuit, thus causing the motor to speed up as long as the operator continues to press the push button SU. After the strip has regained its proper catenary loop, the operator releases the button and the motor slows down to its normal operating speed as governed by the Ward-Leonard control system. Under normal operating speeds the current passes through only a portion of the field rheostat. If the operator pushes a button marked SD he causes the current to completely by-pass the resistance of the field rheostat, thus slowing down the speed of the motor. The motors in question are D. C. shunt motors whose speed can be varied either by varying the voltage to the armature, as does the Ward-Leonard control, or by varying the resistance of the field circuit which is accomplished by the field rheostat. In this type of electric motor the speed is increased when a resistance is introduced into the field circuit.

As stated above, the motor driving the master pinch rolls T operates at one given constant speed through the Ward-Leonard control system which varies the voltage carried in the busses 200 and 201. Thus the speed of the motor driving the master pinch rolls T is governed by varying the voltage to the armature of the same.

The speeds of the motors driving the take-up reels X¹ through X⁷ are controlled both by the Ward-Leonard system and the means as already described in connection with the control unit V. The position of armature 79 in the stationary solenoid 80 governs the magnetic reluctance of the solenoid, which change is transmitted to a Thyratron tube circuit. The Thyratron circuit and solenoids 80 are energized by suitable A. C. current. The fields of the motors for the take-up reels are bucked by secondary fields that are controlled by the Thyratron circuit thus causing the speed of the motors to vary, depending upon the position of the armature 79 within the solenoid 80. The position of the armature is automatically controlled by the amount of tension on the strip between the master pinch rolls T and the take-up reels X. When the strip is under minimum tension, the armature 79 is fully positioned within the solenoid 80, thus effecting the minimum amount of magnetic reluctance and there-

by causing the Thyatron circuit to react correspondingly to speed up the motors by increasing the bucking influences of the secondary fields. If the armature 79 is withdrawn from the solenoid, the magnetic reluctance of the solenoid is increased, thus causing the Thyatron circuit to slow down the speed of the motors by decreasing the bucking characteristics of the secondary fields.

The heating furnace is shown in Figs. 22 and 23, which comprise chamber 150 containing upper and lower contact bars between which the courses of the strip travel during the heating. Vertical reinforcing bars 156 are shown as being disposed along the furnace, which is surmounted by a frame 158 on which the signal lights and bells are mounted for operation as described above, and as will be understood from the drawings, and particularly Figure 24A, whenever any substantial variation in the curvature of the courses of strip passing through the furnace, either up or down, the resulting change in curvature will cause disaligned strip to contact either the upper or lower bar, and actuate the corresponding signal for notifying an operator that adjustment is needed. The furnace is provided with a sight opening as shown, and outlets for the contact bars for leads interconnecting the bars and signals.

From the foregoing it will be seen that we have provided a means for continuously passing strip through a zone of treatment in such a manner that the strips will always advance at a uniform rate, unimpeded by intermittent articulating and stripping operations, and this without limitation as to the width or number of strips being processed, so long as the maximum limitations for which the line might be designed are not exceeded.

While we have illustrated and described one specific form of apparatus for carrying out our invention, it will be understood that we do not wish to be limited thereto, since various modifications and changes will readily suggest themselves to those skilled in the art, and many of such modifications and changes may be made without departing from the scope of our invention as defined in the appended claims.

We claim:

1. In apparatus for continuously treating metal strips, wherein a plurality of strips are passed simultaneously through a train of treating instrumentalities, the combination which comprises a plurality of stands of rolls including driven pinch rolls, each strip being passed over its respective roll in a path which is laterally displaced from the paths of travel of the remaining strips of the plurality, the said stands of pinch rolls receiving the strips from a supplying station and delivering the strips in horizontal noncoplanar relation, instrumentalities for restoring the strips to substantially horizontal coplanar relation, a stand of master rolls for receiving the strips, means for driving the master rolls at a continuously constant speed for giving constant speed of travel to all strips, means for synchronizing the master rolls and the driven pinch rolls, and control means for the driven pinch rolls for correcting any asynchronous condition between the driven pinch rolls and the master rolls.

2. In apparatus for continuously treating metal strip, wherein a plurality of strips are passed simultaneously through a train of treating instrumentalities, the combination which comprises a plurality of stands of rolls including driven pinch rolls, each strip being passed over its respective roll in a path which is laterally displaced from the paths of travel of the remaining strips of the plurality, the said stands of driven pinch rolls being positioned in horizontal planes and receiving and delivering the strips in horizontal noncoplanar relation, instrumentalities for restoring the strips to horizontal coplanar relation, a stand of master rolls for receiving the strips, means for driving the master rolls at a continuously constant speed for giving constant speed of travel to all the strips, and means for synchronizing the master rolls and the driven pinch rolls.

3. In apparatus for continuously treating metal strip, wherein a plurality of strips of different widths are passed simultaneously through a train of treating instrumentalities, the combination which comprises a plurality of stands of rolls including driven pinch rolls of different widths corresponding to different widths of the strips, each width of strip being passed over its respective roll in a path which is laterally displaced from the paths of travel of the remaining strips of the plurality, the said stands of pinch rolls receiving the strips from the supplying station and delivering the strips in horizontal noncoplanar relation, a stand of master rolls for receiving the strips, instrumentalities for restoring the strips to substantially horizontal coplanar relation, means for driving the master rolls at a continuously constant speed for giving constant speed of travel to all strips, means for synchronizing the master rolls and the driven pinch rolls, and control means for the driven pinch rolls for correcting any asynchronous condition between the driven pinch rolls and the master rolls.

4. In apparatus for continuously treating metal strip, wherein a plurality of strips of different widths are passed simultaneously through a train of treating instrumentalities, the combination which comprises a plurality of stands of rolls including driven pinch rolls of different widths corresponding to the widths of the strips, each width of strip being passed over its respective roll, in a path which is laterally displaced from the paths of travel of the remaining strips of the plurality, the said stands of driven pinch rolls being positioned in different horizontal planes, and receiving and delivering the strips in horizontal noncoplanar relation, a stand of master rolls for receiving the strips, instrumentalities for restoring the strips to substantially horizontal coplanar relation, means for driving the master rolls at a continuously constant speed of travel to all the strips, means for synchronizing the master rolls and the driven pinch rolls, and control means for the driven pinch rolls for correcting any asynchronous condition between the driven pinch rolls and the master rolls.
